UNITED STATES PATENT OFFICE.

EDWARD E. FOSTER, OF BEVERLY, MASSACHUSETTS.

MACHINE FOR OPERATING UPON CASTING PATTERNS.

Application filed November 22, 1922. Serial No. 602,602.

The present invention relates to machines for operating upon casting patterns, and more particularly to a machine for operating upon casting patterns, having marginal flanges, which determine the form of the leaders used in automatic shoe machines. These leaders are now made by producing a sole-shaped blank having the shrinkage of cast iron and the spring of the last measurements incorporated therein, and then inserting the blank into a machine provided with automatic mechanism for winding a strip of paper around the edge of the blank to form a flange thereon. After the pattern is removed from this machine it is often found that the flange is somewhat loose and that its top and bottom faces are rough owing to projecting edges of the paper due to inequalities in the wind. Before the pattern can be used to cast the leaders it is desirable to compress the flange laterally and iron out the roughness on its top and bottom faces.

The object of the present invention is to produce a machine for compressing and ironing the flange.

To the accomplishment of this object, and such others as may hereafter appear, the features of the invention relate to certain devices, combinations, and arrangements of parts hereinafter described, and then set forth broadly and in detail in the appended claims, which possess advantages readily apparent to those skilled in the art.

The various features of the present invention will be best understood from an inspection of the accompanying drawings illustrating the best form of invention at present known to the inventor, in which,

Figure 1 is a plan of a machine for operating upon the casting patterns;

Fig. 2 is a left side elevation, the casting pattern being shown in section;

Fig. 3 is a sectional elevation on the line 3—3, Fig. 1, the casting pattern, however, being removed;

Fig. 4 is a detail in front sectional elevation on the line 4—4, Fig. 3; and

Fig. 5 is a detail in left side sectional elevation showing the manner in which the various rolls of the machine are separated to facilitate the insertion and removal of the casting pattern.

In the illustrated embodiment of the invention a casting pattern 1 (Fig. 1) is mounted on a table 2 carried by the machine 55 column 3. As shown in Figures 1 and 2, the casting pattern comprises a sole-shaped body portion 4 provided with a peripheral flange 5. The casting patterns operated upon by the machine disclosed in my former Patent 60 No. 1,284,858, November 12, 1918, are of the single face type, that is, capable only for use in casting a leader for a left or a right shoe. For that reason in addition to compressing the flange laterally it was also necessary to impart a draft to the flange in order to facilitate the removal of the casting pattern from the sand.

The casting patterns shown in position for operation in the drawings of the present 70 case are of the double faced type, that is designed to cast a leader which may be used in an operation on a left shoe and then by being reversed used in an operation on the mate or right shoe. As the flanges of these 75 casting patterns of the double faced type are provided with upper and lower external bevels in the machine disclosed in my Patent No. 1,267,842, May 28, 1918, there is no need of providing the pattern with a draft as 80 the double bevel permits the ready removal of the pattern from the casting sand. It is, however, necessary to consolidate the flange by compressing it laterally and also to iron 85 the top and bottom faces of the flange to remove the irregularities of the paper wind.

The machine of the drawing is provided with a set of rolls which embrace the flange to consolidate it and iron out the inequalities at the same time driving the pattern over the 90 surface of the table 2 and swinging it laterally to transfer the point of operation of the rolls around the sole-shaped curvature of the flange.

The upper face of the pattern and the inner upper face of the flange are engaged by a roll 6 mounted to rotate upon a pin 7 which is secured to a head 8. The head 8 is carried by a yoked frame 9 having a pair of legs 10 which are pivotally mounted upon 95 a pair of brackets 11 secured to the table 2.

Journaled in the frame 9 is a longitudinal shaft 12 the front end of which carries a disc roll 13 arranged to engage the top face

of the flange (Fig. 3). The rear end of the shaft 12 carries a gear 14 which meshes with a similar gear 15 on a second horizontal shaft 16. One end of the shaft 16 is journaled in a bearing 17 secured to the table 2. The other end of the shaft 16 is journaled in a slide 18 (Fig. 4) mounted to slide in ways 19 carried by the table 2. The shaft 16 carries at one end a disc roll 20 arranged 10 to engage the bottom face of the flange (Fig. 3). The shaft 16 is driven through a worm wheel 21 secured to the gear 15 and engaged with a worm 22. The worm is secured to a horizontal shaft 23 journaled beneath the table 2 and driven from some source of power through the belt pulley 24 (Figs. 1 and 2).

The bottom face of the pattern and the lower inside face of the flange are engaged 20 by a roll 25 which is mounted to rotate upon a pin 26 carried by a head 27 secured to the table 2. The outside face of the pattern is engaged by a roll 28 which is carried by a bevel gear 29 driven from the shaft 16 25 through a bevel gear 30 splined to the shaft.

The roll 28 is backed by a heavy spring pressure to effect a lateral compressing action on the flange held between the roll 28 and its cooperating rolls 6 and 25. To this 30 end the shaft 16 carries a spring 31 coiled around the shaft and interposed between the worm wheel 21 and a sleeve 32 which is splined on the shaft and which carries the gear 30. The spring 31 also acts through 35 connections to be described to force the roll 6 towards the roll 25.

In order to withdraw the rolls 6 and 28 from the work against the pressure of the spring 31 to facilitate insertion and removal 40 of the work the frame 9 carries a pair of pivoted links 33 to which a handle 34 is pivoted (Figs. 3, 4, and 5). The handle 34 is extended as a yoked bell crank lever 35 pivoted at 36 on the column 3. The short arms 45 37 (Fig. 4) of the lever 35 engage a bearing cap 38 carried by the slide 18 and interposed between flanges 39 formed on the sleeve 32. With this construction pressure on the handle 34 simultaneously tips the frame 9 and 50 slides the sleeve 32 into the positions of Fig. 5. From an inspection of Fig. 3 it will be apparent that the axis about which the frame 9 tips intersects the common pitch line of the gears 14 and 15 at a point thereon farthest from the work so that the rotation of 55 the driven rolls may not be interrupted during the removal or insertion of the work.

The rolls 13 and 20 cooperate to feed the pattern longitudinally over the table 2 and 60 iron out any inequalities on the top and bottom faces of the flange. The rolls 6, 25 and 28 cooperate to compress the flange and swing the pattern laterally to maintain the various curvatures of the flange at the operating point in the line of feed.

What is claimed as new, is:—

1. A machine for operating upon a casting pattern having a marginal flange, having, in combination, a pair of rolls arranged to engage the top and bottom faces of the 70 pattern, respectively, a roll arranged to engage the outside face of the flange, and a single means for relatively moving two of the rolls in two directions.

2. A machine for operating upon a casting 75 pattern having a marginal flange, having, in combination, a pair of rolls arranged to engage the top and the bottom faces of the flange, respectively, a roll arranged to engage the outside face of the flange, and a 80 single means for relatively moving two of the rolls in two directions.

3. A machine for operating upon a casting pattern having a marginal flange, having, in 85 combination, a pair of rolls arranged to engage the top and bottom faces of the flange, respectively, a roll arranged to engage the outside face of the flange, and positively operating mechanism for driving the three 90 rolls.

4. A machine for operating upon a casting pattern having a marginal flange, having, in combination, a pair of rolls arranged to engage the top and bottom faces of the flange, respectively, a roll arranged to engage the outside face of the flange, positively 95 operating mechanism for driving the three rolls, and means for relatively moving two of the rolls in two directions.

5. A machine for operating on a casting 100 pattern having a marginal flange, having, in combination, a roll arranged to engage the top face of the pattern, a roll arranged to engage the top of the flange, a tipping frame for said rolls, a roll arranged to engage the 105 outside face of the flange, a roll arranged to engage the bottom of the flange, and a single means for tipping the frame and relatively moving the last two named rolls.

6. A machine for operation on a casting 110 pattern having a marginal flange, having, in combination, a roll arranged to engage the top face of the pattern, a roll arranged to engage the outside face of the flange, and a spring arranged to hold both rolls in operating 115 position.

7. A machine for operating on a casting pattern having a marginal flange, having, in combination, a roll arranged to engage the top face of the pattern, a roll arranged to engage the outside face of the flange, a spring arranged to hold the rolls in operating position, and means for withdrawing the rolls from operating position against the 120 pressure of the spring.

8. A machine for operating upon a casting pattern having a marginal flange, having, in combination, a pair of rolls arranged to engage the top and bottom faces of the flange, respectively, a shaft for each roll, an inter- 130

meshing gear on each shaft, and means for tipping one of the shafts about an axis intersecting the common pitch line of the gears at the point thereon farthest from the rolls.

9. A machine for operating upon casting patterns having a marginal flange, having, in combination, a pair of feeding rolls, a

pair of compressing rolls, a tipping frame for one of the feeding rolls, a sliding frame for one of the compressing rolls, and a single **10** means for tipping and sliding the frames.

In testimony whereof I have signed my name to this specification.

EDWARD E. FOSTER.
